UNITED STATES PATENT OFFICE.

HERMAN F. RIESCHICK, OF FALLS CITY, NEBRASKA.

LOCK-NUT.

No. 844,750.

Specification of Letters Patent.

Patented Feb. 19, 1907.

Application filed December 12, 1906. Serial No. 347,446.

To all whom it may concern:

Be it known that I, HERMAN F. RIESCHICK, a citizen of the United States, residing at Falls City, in the county of Richardson 5 and State of Nebraska, have invented certain new and useful Improvements in Lock-Nuts, of which the following is a specification.

This invention relates to lock-nuts for 10 bolts; and it has for its object to present a self-locking nut of simple and improved construction, which by simply tightening it upon the bolt will engage the surface against which it is tightened in such a manner as to 15 prevent it from working loose by shaking or rattling of the parts or from other ordinary causes.

A further object of the invention is to present a self-locking reversible nut having two 20 opposite locking-faces, either one of which may be placed in locking engagement with the surface against which the nut is tightened.

Still further objects of the invention are to 25 simplify and improve the construction and operation of this class of devices.

With these and other ends in view, which will readily appear as the nature of the invention is better understood, the same consists in the improved construction and novel 30 arrangement and combination of parts, which will be hereinafter fully described, and particularly pointed out in the claims.

In the accompanying drawings has been 35 illustrated a simple and preferred form of the invention, it being, however, understood that no limitation is necessarily made to the precise structural details therein exhibited, but that changes, alterations, and modifications within the scope of the invention may 40 be resorted to when desired.

In the drawings, Figure 1 is a plan view of 45 a lock-nut constructed in accordance with the principles of the invention. Fig. 2 is an inverted plan view of the same. Fig. 3 is a transverse sectional view taken on the line 3 3 in Figs. 1 and 2. Fig. 4 is a perspective view. Fig. 5 is a transverse sectional view showing the nut tightened upon a bolt. Fig. 50 6 is a plan view showing a slightly-modified form of the nut. Fig. 7 is a side view of the modified form.

Corresponding parts in the several figures are denoted by like characters of reference.

The body 1 of the improved lock-nut may 55 be square, as shown in the drawings, or of

any other suitable and desirable shape or conformation and of any desired size and dimensions, said body being provided with the centrally-disposed threaded aperture 2, engaging the bolt 3, which latter is of ordinary construction.

One face F of the nut is provided with radially-disposed ratchet-grooves 4, extending from the central aperture to the edges of the nut. The number of these ratchet-grooves may be varied. In Figs. 1 and 4 of the drawings four such grooves have been shown, while in Fig. 6 of the drawings there are only two. Under the construction shown in Fig. 4 of the drawings the front 70 walls 5 of the ratchet-grooves are at right angles to the face F of the nut. In Fig. 7 of the drawings the front walls, here designated 5^a, are slightly undercut in order to form a relatively sharp engaging edge 6 to prevent 75 reverse rotation of the nut after the latter has been tightened, as will presently appear. The opposite face G of the nut is provided with radially-disposed grooves 7, which may be of approximately U-shaped or V-shaped 80 cross-section. In the process of stamping or forming said grooves small portions of metal may be forced or upset in an inward direction, so as to overhang the central threaded aperture 2, said overhanging portions forming sharp-pointed fins 8, which will have a tendency to grip the bolt and to prevent the rotation of the nut thereupon.

In operation the improved lock-nut is reversible and either of the faces F or G may 90 be exposed to and placed in engagement with the surface 9, against which the nut is to be tightened, the ratchet-grooves 4 being particularly intended for engagement with metallic and other hard surfaces, while 95 the grooves 7 are especially adapted for co-operation with surfaces of wood and other similar relatively yielding material. When the nut is tightened against the surface 9, the latter will be free to expand in the grooves 4 or 7, such expansion being due to the inherent resiliency of all material to a greater or less degree. Such expansion within the grooves 4 or 7 will naturally obstruct the reverse rotation of the nut, which will thereby 100 become locked upon the bolt. In case of the ratchet-grooves the sharp edges of the front walls of said grooves will positively engage the material of the surface 9 and serve to lock the nut. The sharp-pointed fins 8 by 105 110

gripping the bolt will create a degree of friction which will materially assist in locking the nut.

Having thus described my invention, I claim and desire to secure by Letters Patent of the United States—

A reversible self-locking nut provided with ratchet-grooves in one of its faces and provided in its opposite face with radial grooves

at the inner ends of which are formed sharp-pointed fins overhanging the central threaded aperture of the nut.

In testimony whereof I affix my signature in presence of two witnesses.

HERMAN F. RIESCHICK.
